GOLF CLUB SHAFT

Filed May 26, 1926

Inventor

Henry K. B. Davis.

By Walter W. Burne

Attorney

UNITED STATES PATENT OFFICE

HENRY K. B. DAVIS, OF NEW YORK, N. Y., ASSIGNOR TO SWINGRITE CO., INC., OF PROVIDENCE, RHODE ISLAND

GOLF-CLUB SHAFT

Application filed May 26, 1926. Serial No. 111,680.

This invention relates to shafts for golf clubs and particularly to those clubs which are built up.

There are many difficulties with the usual 5 golf club shaft found upon the market today. The hickory shafts are too soft and provide too much flexibility necessitating the culling of a large number of shafts to find the required number of shafts of proper flexibility 10 for the first grade clubs. Ash has been tried but is also too soft and too flexible to give the best results.

Steel shafts have been in some instances 15 been found to give good results, but the average good golf player will not use it as it is considered by some, to be too "quick". In other words, there is a different air resistance in the downward stroke which requires an alteration in style of stroke. To increase the 20 size of the steel shaft to produce the desired air resistance would mean an increase in the weight of the club or a decrease in the thickness to such a degree that it would be difficult to work in manufacture.

25 The primary object of my invention is to provide a built up shaft which in addition to having the advantages usually found in built up structures such as uniform quality and resistance to weather conditions, can be made 30 to combine the qualities of any two materials to be used to produce in the shaft the qualities of the materials in a varying degree depending upon the position and amount of the materials used, in other words to obtain the 35 exact desired effect.

Another object of the invention is the provision of a golf club shaft which has the proper torsional and bending flexibilities while at the same time has the proper cross 40 section and with a decrease in weight.

Other and further objects of this invention will be apparent to one skilled in the art, from a reading of the complete specification and claims.

45 Referring to the drawing wherein I have illustrated one embodiment of my invention.

Fig. 1 is a perspective view of a golf club shaft made according to my invention.

Figs. 2 and 3 are enlarged cross sectional 50 views made perpendicular to the axis of the

shaft at about the positions of the lines 2—2 and 3—3, respectively.

In carrying out my invention I have selected, for example, two materials which have produced remarkably good results. 55 These are bamboo and hickory. It has been found in actual practice that a six sectional shaft made according to my invention as illustrated provides a structure which produces in actual practice an increase in flight 60 yards which I explain as being probably due to a combination of the qualities of the two materials and the construction which takes advantage of these qualities.

In the embodiment herein illustrated, I 65 show a shaft made having six sections, each section having two surfaces which are adjacent surfaces of adjacent sections and which lie in planes at 60° to each other.

In the embodiment illustrated I have indicated three alternate sections which are made of bamboo and are designated by the numeral 10. It will be observed that these sections in a portion of the shaft, terminate short of the axis of the shaft and provide a 70 space which in my preferred form, I have filled with glue and have designated at 11. At another portion of the shaft, in the embodiment illustrated, it will be observed that the sections 10 and 12 all extend substantially to 75 the axis of the shaft, thus leaving no space in 80 the interior of the body of the shaft.

Between the alternate sections 10 of bamboo, I have illustrated, sections of hickory 12 85 which are suitably secured to the sections 10 by glue. It is to be noted that the grains of wood in my preferred form are shown so that the grain edges are to the outside.

In the manufacture of my improved shaft, the pieces are cut to desired size and shape to 90 produce the desired effect and the faces to be secured together are made to a proper angle so that when assembled there will be practically no space between any two adjacent faces.

95 From the above, it will be seen that I have combined the characteristics of the two materials to produce a structure which has the good characteristics of both materials. For example, the stiffness of the bamboo is offset 100

by the lack of stiffness of the other wood as hickory. This combination gives a structure having the correct amount of bendability. Further the hickory gives torsional strength to the shaft and prevents breaking which might occur in an all-bamboo structure. These advantages have been obtained while still making possible the maintaining of the standard size shaft and at an actual saving 10 in weight to be handled.

While I have shown and described an embodiment of my invention in detail, I desire to have it understood that I do not limit myself to the exact details of the showing and 15 description but that modifications and changes may be made in the materials and number, relative number, shape, relative size cutting with relation to grain and angles of cut of the pieces, without departing from the 20 spirit of my invention and within the scope of the appended claims.

Having described my invention what I claim is:—

1. A shaft for golf clubs having a plurality 25 of sections secured together, two of the adjacent sections being of different material and having adjacent surfaces in planes passing substantially through the axis of the shaft, some of the sections having portions 30 ending short of the axis of the shaft and other sections extending substantially to the axis of the shaft.

2. A shaft for golf clubs having a plurality 35 of sections secured together, the adjacent sections being of different material and having adjacent surfaces in planes passing substantially through the axis of the shaft, alternate sections of the shaft having portions stopping short of the axis of the shaft and the sections 40 therebetween extending substantially to the axis of the shaft.

3. A shaft for golf clubs having a plurality 45 of sections secured together, the adjacent sections being of different material and having adjacent surfaces in planes passing substantially through the axis of the shaft, alternate sections of the shaft having portions stopping short of the axis of the shaft and the sections 50 therebetween having portions extending substantially to the axis of the shaft, the spaces between the alternate sections and the axis being filled with a suitable glue-like substance.

4. A shaft for golf clubs having a plurality 55 of sections secured together, the adjacent sections being of bamboo and another wood, respectively, and having adjacent surfaces in planes passing substantially through the axis of the shaft, some sections of the shaft 60 having portions ending short of the axis of the shaft and other sections extending substantially to the axis of the shaft.

In testimony whereof I hereunto affix my 65 signature.

HENRY K. B. DAVIS.
